UNITED STATES PATENT OFFICE.

CHARLES F. KURZ, OF CLEVELAND, OHIO.

CASE OR CABINET HAVING SLIDING DOORS.

No. 920,158.

Specification of Letters Patent.

Patented May 4, 1909.

Application filed October 24, 1908. Serial No. 459,337.

To all whom it may concern:

Be it known that I, CHARLES F. KURZ, a citizen of the United States of America, residing at Cleveland, in the county of Cuyahoga and State of Ohio, have invented certain new and useful Improvements in Cases or Cabinets Having Sliding Doors; and I hereby declare the following to be a full, clear, and exact description of the invention, 10 such as will enable others skilled in the art to which it pertains to make and use the same.

This invention relates to an improved case or cabinet having the following:—a chamber and a doorway affording access to the said 15 chamber; laterally spaced tracks arranged on the bottom and longitudinally between the side walls of the doorway; upwardly movable doors mounted on and shiftable endwise of the different tracks respectively 20 and having their upper portions provided with bearing surfaces, and means whereby the said bearing surfaces are guided during the movement of the doors on the tracks without interfering with the lifting of the 25 doors and with the removability of the lifted doors forwardly from the doorway.

The primary object of this invention is to have the doors so connected with the tracks and with the top wall of the doorway that 30 forward and rearward displacement of the doors is prevented and the doors are free to be lifted and removed forwardly from the doorway to afford convenient access to the inner side of the glass of the doors for cleaning purposes.

Another object is to construct a case or cabinet of the character indicated having the said doors slanting upwardly and rearwardly without interfering with their being lifted 40 and removed from the doorway.

With these objects in view, and to the end of realizing other advantages, such, for instance, as simplicity and convenience, this invention consists in certain features of construction, and combinations of parts, herein-after described, pointed out in the claims and illustrated in the accompanying drawings.

In the said drawings, Figure 1 is a front 50 side view of a case or cabinet embodying my invention. Fig. 2 is a vertical section on line 2—2, Fig. 1, looking in the direction indicated by the arrow. Fig. 3 is a vertical section corresponding with Fig. 2, except 55 that in Fig. 3 the doors are shown lifted preparatory to their removal forwardly from

the case or cabinet. Fig. 4 is a section on line 4—4, Fig. 2, looking forwardly.

Portions are broken away in the drawings to reduce their size, and Figs. 2, 3 and 4 are 60 drawn on a larger scale than Fig. 1.

Referring to the drawings, A indicates the case or cabinet which has a chamber a, and a doorway 7 arranged at the front of the case or cabinet and affording access to the said 65 chamber. The bottom 8 of the doorway slopes downwardly and rearwardly toward the bottom 10 of the chamber a.

Suitably secured to the bottom 8 of the doorway are two stationary metal bars B 70 which are arranged side by side and longitudinally between the side walls of the doorway. Each bar B is provided at its upper side and centrally between the longitudinal edges of the bar with an upwardly projecting 75 flange b which extends longitudinally of the bar. Each flange b forms a track for a door D which has a glass or transparent panel D' and is mounted on and shiftable endwise of the track, which door extends longitudinally 80 of the engaging track a distance enough shorter than the distance between the side walls of the doorway to accommodate the movement of the door endwise of the track. My improved case or cabinet is provided 85 therefore with two laterally spaced stationary tracks b and b arranged on the bottom of the doorway and longitudinally between the side walls of the doorway.

Each door D is shown slanting upwardly 90 and rearwardly and I would here remark that slanting doors of the character indicated are not infrequently more desirable for an effective and convenient display of certain merchandise than vertically arranged doors. 95

Each door D is provided, in its upper edge and about centrally between the forward and rear sides of the door, with a recess 12 which extends from end to end of the said edge, which recess is engaged by a stationary 100 wooden bar 13 which is arranged longitudinally of the said edge and glued or otherwise attached to the wooden top wall 9 of the doorway. Preferably the recess 12 extends vertically downwardly from the upper edge 105 of the door and has its rearwardly facing forward side wall resting against the forward side of the said bar 13 which in conjunction with the opposite side wall of the said recess constitutes a stop for preventing forward 110 displacement of the upper portion of the door. The top wall of the doorway is pro-

vided therefore with two laterally spaced guide-bars 12 which are arranged longitudinally between the side walls of the doorway and engage the recess 12 in the upper edge of the different doors respectively.

By the construction hereinbefore described it will be observed that each door D has its upper portion provided with a rearwardly facing bearing surface which is formed 10 by the rearwardly facing forward side wall of the recess 12 of the said door, and that the bar 13 engaging the said recess constitutes means for guiding the said bearing surface during the movement of the door on the engaging track.

The connection between each door and the engaging track is preferably through the medium of antifriction rollers d which are grooved circumferentially, as at 14. Each 20 door is provided with a plurality of rollers d which are spaced longitudinally of the door and arranged to move on and straddle the track on which the door is mounted and hence the door has to be lifted far enough to 25 render it movable forwardly from the doorway. Each roller d of each door is preferably arranged within a recess 15 formed at the rear side and lower edge of the door and supported from the door in any approved manner.

Each door D is enough smaller in dimensions vertically than the doorway to accommodate lifting of the door, as shown in Fig. 3, far enough to remove its rollers from the 35 engaging track and thereby permit the removal of the door forwardly from the doorway, and the recess 12 in the upper edge of the said door extends far enough below the guide-bar engaging the said recess to accommodate the said lifting of the door. Preferably also the guide-bar is somewhat rounded at the junction of the rear sides and lower edges, and the side walls of the recess 7 are enough farther apart than the forward and 40 rear sides of the engaging bar to facilitate a removal of the door forwardly from the doorway when the door has been lifted from the engaging track as shown in Fig. 3, and more especially to permit the door, upon being 45 lifted, to be swung forwardly somewhat preparatory to fully removing the door from the doorway.

What I claim is:

1. In a case or cabinet having a chamber 55 and a doorway affording access to the chamber; laterally spaced tracks extending between the side walls of the doorway at the bottom of the doorway, and upwardly movable doors mounted on and shiftable endwise 60 of the different tracks respectively and requiring to be lifted to render them movable forwardly from the doorway, each door and the top wall of the doorway having the one

a recess and the other a guide-forming portion projecting into the said recess, said 65 guide-forming portion and said recess being arranged longitudinally of the travel of the door and being long enough to cause the said recess to be engaged by the said guide-forming portion in any position of the door, 70 and the said recess being large enough in dimensions vertically and transversely to permit the lifting of the door and the removal of the lifted door forwardly from the doorway.

2. In a case or cabinet having a chamber and a doorway affording access to the chamber; laterally spaced tracks extending longitudinally between the side walls of the doorway at the bottom of the doorway; upwardly movable doors mounted on and shiftable endwise of the different tracks respectively and requiring to be lifted to render them movable forwardly from the doorway, each door being provided in the top 80 edge thereof and intermediately the forward and rear sides of the door with a recess which extends from end to end of the said edge, and a stationary guide-bar projecting into and arranged longitudinally of the said 85 recess, and the said recess extending far enough downwardly below the guide-bar, and the door having the said recess being loose enough relative to the guide-bar to permit lifting of the door and the removal 90 of the lifted door forwardly from the doorway.

3. In a case or cabinet having a chamber and a doorway affording access to the said chamber; laterally spaced tracks extending 100 longitudinally between the side walls of the doorway at the bottom of the doorway; upwardly movable doors mounted on and shiftable endwise of the different tracks respectively and requiring to be lifted to render them movable forwardly from the doorway, each door being provided in the top edge thereof and intermediately the forward and rear sides of the door with a recess which extends from end to end of the said edge, 105 and a stationary guide-bar projecting into and arranged longitudinally of the said recess and rounded at its rear side and lower edge and the said recess being wide enough and extending a suitable distance downwardly below the guide-bar relative to the guide-bar to permit lifting of the door and the removal of the lifted door forwardly from the doorway.

In testimony whereof, I sign the foregoing 120 specification, in the presence of two witnesses.

CHARLES F. KURZ.
